HOLDER FOR HAIR CURLERS OR THE LIKE

Frank Di Domenico, Mount Holly, N.J., assignor of fifteen percent to Raymond J. Mawhinney and
A. Robert Theibault, both of Kensington, Md.

Filed Mar. 22, 1962, Ser. No. 69,384

Term of patent 14 years

(Cl. D58—13)

FIG. 1.

FIG. 2.

FIG. 3.

FIG. 4.

FIG. 5.

FIG. 6.

FIGURE 1 is a top perspective view of a holder for hair curlers or the like, showing my new design;

The opposite side of my design to that shown in FIGURE 5 is identical therewith.

I claim:

The ornamental design for a holder for hair curlers or the like, as shown and described.
